AUTOMATIC TELEPHONE SYSTEM

Max Langer, Hermsdorf, near Berlin, Germany,
assignor to Siemens & Halske Aktiengesellschaft, Siemensstadt, near Berlin, Germany

Application July 15, 1932, Serial No. 622,603
In Germany July 29, 1931

5 Claims. (Cl. 179—16)

The invention is in the nature of an improvement over a prior application of Langer et al., Ser. No. 594,086, filed February 19, 1932, now Patent No. 1,925,261, granted Sept. 5, 1933, which relates to a circuit arrangement for automatic telephone systems so arranged that when impulses are transmitted for the setting of numerical impulse receivers a lead passing to an impulse receiver to be set by said impulses is placed at the disposal of the station setting up a connection which then has exclusive use thereof.

The present invention shows a special method of solving the feature of the invention covered by the said prior application; and this method is that, upon the reception of an impulse of a series, switching means for the setting of numerical impulse receivers place a lead passing to an impulse receiver to be set by this impulse series at the disposal of a station setting up a connection, said station only being able to utilize this lead.

Two embodiments of the invention are shown in the drawing. Fig. 1 shows a group selector I GW1 connected in parallel with a secondary lineswitch MW1 which seizes a line accessible to it when the first impulse series is transmitted by delaying the repeating of the first impulse in such a manner that the secondary lineswitch hunts for and then guards an idle junction line between receiving and retransmitting the impulse.

Fig. 2 shows a group selector I GW2 connected in parallel with a secondary lineswitch MW2 which on the transmission of the first impulse of a series hunts for and then guards an idle junction line while suppressing this impulse from the group selector which succeeds said secondary lineswitch.

The individual switching operations in detail are as follows:

When the calling subscriber reaches the arrangement shown in Fig. 1 over any associated connecting devices, relay A is energized over the subscriber's line loop and thereafter relay C over the test lead in a manner of no interest in this case. When the subscriber sends out impulses, that is to say cuts off the energizing current for relay A passing over the speaking lead, relay Y is energized in the following circuit on the first release of relay A: earth, contacts 10c, 9a, windings I and II of relay Y, battery, earth. In addition, due to the closing of contacts 17a an energizing circuit for the rotary magnet DMW1 of the secondary lineswitch MW1 is closed over: earth, battery, rotary magnet DMW1, contacts 17a, 18c, 19p2, relay interrupter RU, earth. The rotary magnet is operated in this circuit until the secondary lineswitch MW1 has reached an idle

group selector, for example the not-shown group selector I GW2. The secondary lineswitch MW1 is of the high speed type and may have from one to ten trunk lines accessible thereto depending upon its speed. Switches of this type having a speed of 200 steps per second have been designed and as incoming impulses to relay A may be only ten per second contact 17a will be closed long enough for switch MW1 to select an idle trunk. When this occurs, relay P2 is energized over a not-shown potential over the test lead: test potential, wiper of the secondary lineswitch MW1, relay P2, contacts 20a, 22c, rotary off-normal contact 23w of the group selector I GW1, earth. Relay P2 locks itself at 21p2 and brings the secondary lineswitch to rest by opening contact 19p2.

When relay A is now energized, the vertical magnet HGW1 of the group selector I GW1 operates over the circuit below due to contact 11a being closed since relay Y remains energized during the impulse series as it operates as a slow-acting relay: earth, contacts 13c, 12y, 11a, rotary off-normal contact 27w of the group selector I GW1, vertical magnet HGW1, battery, earth. The group selector takes one vertical step. The not-shown group selector I GW2 reached by the secondary lineswitch MW1 executes a vertical step in the same manner by influencing its impulse receiving relay corresponding to relay A in the following circuit: earth, contacts 1c, 3a, 2p1, 8p2, and wiper of the secondary lineswitch MW1. Thus impulses are repeated by relay A on its energization instead of on its deenergization as in the prior circuits. In a similar manner every additional line loop breaking and closing during the impulse series causes a vertical movement on the part of the group selectors I GW1 and I GW2.

At the end of the impulse series, relay Y is deenergized due to the prolonged energization of relay A over the subscriber's line loop, with the result that, due to the off-normal contact 26k being closed after the vertical movement of the group selector I GW1, the rotary magnet DGW1 of the group selector I GW1 operates over: earth, battery, rotary magnet DGW1, contacts 14y, 16p1, off-normal contact 26k of the group selector I GW1, contact 25dGW1, earth. The rotary magnet DGW1 influences contact 25dGW1 in such a manner that said rotary magnet operates as a self-interrupter and consequently advances the group selector I GW1 step by step in the reached level. After its vertical movement, the not-shown group selector I GW2 also is advanced

- step by step in the reached level in a similar manner.
- Assuming that the subscriber dials the digit 4 and consequently transmits four impulses, the two group selectors are raised to the fourth level and the group selector I GW1 closes the level contact 24dk4. Since an impulse series comprising four impulses corresponds to the traffic direction passing over the group selector I GW2 10 the energizing circuit for relay P2 is maintained over the level contact 24dk4 after the rotary off-normal contact 23w of the group selector I GW1 has been opened. The not-shown group selector I GW2 consequently hunts for an idle junction 15 line in the reached level. The group selector I GW1 on the other hand is advanced to the last contact in the fourth level since no junction lines are connected up in this level. Relay P1 is energized when the last contact has been reached and 20 by opening contact 16p1 deenergizes the rotary magnet DGW1 and consequently stops the rotary movement of the group selector. Further impulse series are now transmitted to additional numerical impulse receivers over: earth, contacts 25 1c, 4a, and 57p1, over the secondary lineswitch MW1 and over the switch wipers of the not-shown group selector I GW2 accessible to said secondary lineswitch and the connection finally completed in this manner.
- If any other number than four impulses have 30 been transmitted, the level contact 24dk4 remains open so that after the first rotary movement of the group selector IGW1, which opens the rotary off-normal contact 23w, relay P2 is deenergized and the secondary lineswitch MW1 releases the group selector I GW2 by opening contact 21p2. The group selector I GW1, however, now hunts for an idle junction line in the reached level and when found is brought to rest on it due to the 35 energization of relay P1 in known manner. Further impulse series are then transmitted over the switch wiper of the group selector I GW1 to the succeeding numerical impulse receivers.
- The circuits required for the release have been 40 omitted, being of no importance for the feature of the invention. The release may be carried out in any suitable manner.
- As previously mentioned, Fig. 2 illustrates a 45 second embodiment of the invention in which the first-received impulse is not delayed when extended further as in the embodiment according to Fig. 1, but instead is suppressed for the not-shown group selector I GW22 which succeeds the secondary lineswitch MW2. The operations in detail are as follows:
- When a calling subscriber has obtained access 50 to the arrangement shown in Fig. 2, relay A1 is energized over the subscriber's line loop and relay C1 over the test lead similarly to the previous case. On the transmission of the first impulse series which for example may comprise four impulses, relay A1 is accordingly deenergized and by intermittently closing contact 43a1 causes the vertical magnet HGW21 to operate in series with relay V1. The off-normal contact 55 41k of the group selector I GW21 is closed after the first vertical step and this causes relay Y1 to respond. An impulse circuit for the rotary magnet DMW2 of the secondary lineswitch MW2 is closed on the first vertical step due to the closing of contact 49a1 while relay A1 is deenergized in response to the first received impulses, whereupon said secondary lineswitch MW2 hunts freely for a succeeding group selector, for example the not-shown group selector I GW22 in the same 60 manner as the switch MW1 (Fig. 1). When this has been reached, relay P22 is energized and by opening contact 51p22 causes the release of the rotary magnet DMW2. The setting of the secondary lineswitch MW2 is thus completed during the transmission of the first impulse. The second impulse, that is to say the second release of relay A1, which causes the group selector I GW21 to be raised to the second level, energizes for the first time the impulse-receiving relay associated with the not-shown group selector I GW22 over: earth, contacts 31y1, 32c1, 33a1, 39p22, wiper of the secondary lineswitch MW2. The further impulses then influence both the group selectors. Relay V1 releases at the end of the impulse series 65 and over its contact 47v1 closes an impulse circuit for the rotary magnet DGW21 with the result that the group selector I GW21 is advanced step by step. The group selector I GW22 is operated in a similar manner. Due to four impulses having been transmitted which characterizes the junction lines accessible over the group selector I GW22, relay P22 remains energized over the level contact 52dk4. The group selector I GW21 operates until the last contact has been 70 reached since no junction lines are encountered and relay P21 is energized as soon as this position is reached. The opening of contact 45p21 brings the group selector I GW21 to rest. Additional impulse series are then transmitted in known manner over the wiper of the secondary lineswitch MW2 and the group selector I GW22.
- The trunk lines are, of course, connected to the banks of switches I GW21 and I GW22, so that the proper group is selected by one less step 75 of the switches than there are impulses transmitted in the first digit to the switch. This digit 4 always causes three steps of the switch and the first impulse received is not repeated. This insures that the line switch can select a 80 trunk over even a large trunk group before the impulse is repeated thereto and thus definitely prevents it from receiving a portion of the repeated impulse before its seizure is completed.
- If the impulse series comprises another number 85 than four impulses, contact 52dk4 is not closed with the result that relay P22 is disconnected at the rotary off-normal contact 53w of the group selector I GW21 after its first rotary step. The not-shown group selector I GW22 is 90 then released. The group selector I GW21, however, continues to advance in the reached level until its wipers encounter an idle junction line. When this occurs it is brought to rest due to the 95 energization of relay P21 and further impulse series are then transmitted over its switch wipers to succeeding numerical impulse receivers.
- The release circuits have been omitted from 100 this arrangement also, since the release is of no importance for the feature of the invention and may be carried out in any suitable manner.
- What is claimed is:
1. In an automatic telephone system, a trunk line accessible to a trunk selecting automatic switch, means effective following the seizure of said automatic switch for starting said switch to operating to select an idle trunk responsive to the first impulse of a series constituting a digit, and means for repeating each of the impulses of the digits subsequent to the first over said 105 trunk line after it has been seized by said automatic switch.
  2. In an automatic telephone system, an automatic switch having access to a group of trunk lines, means effective after said automatic switch 110

has been taken for use for starting said automatic switch to hunting for an idle one of said trunk lines responsive to the first impulse of a series constituting a digit of the desired number, and means for repeating the impulses of said series over the trunk line taken for use by said automatic switch, the said means including means for delaying a repeated impulse so as to allow said switch time to seize an idle trunk before the first impulse is repeated.

3. In an automatic telephone system, an automatic switch having access to a group of trunk lines, means effective after said switch has been taken for use for starting said switch into operation to select an idle one of said trunk lines responsive to the first impulse of a series constituting the next digit in the telephone number, means for repeating the impulses of said series over the idle trunk line taken for use by said switch, and means associated with said switch for entirely suppressing the first of said impulses as regards the repeating thereof over said trunk line, whereby the repeating of a mutilated first impulse is prevented.

25 4. In a combined main exchange and sub-exchange telephone system wherein a switch in the sub-exchange and a switch in the main exchange

are both arranged to respond to the first digit dialled by a sub-exchange subscriber, means in the sub-exchange responsive to the removal of the receiver at a calling substation for taking a sub-exchange switch into use to respond to the first digit dialled, trunk lines leading from the sub-exchange to the main exchange and terminating in main-exchange switches, means for taking one of said trunk lines for use in the sub-exchange, and means for delaying the action of the last-named means until the commencement of the dialling of the first digit in the number, whereby the holding time of said trunk lines is reduced.

5. In a telephone system, an automatic switch having group and line selecting motion, a line relay therefor, trunk lines accessible thereto, means for transmitting impulses to said line relay, means associated with said switch responsive to the first deenergization of said relay for selecting an idle trunk, means responsive to the subsequent energizations of said relay for operating said switch in its group selecting motion and for repeating the received impulses over the selected idle trunk line.
